[57] CLAIM

The ornamental design for a nursing blanket, as shown and described.

DESCRIPTION

FIG. 1 is a perspective view of a nursing blanket showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is a top plan view thereof;

FIG. 8 is a perspective view of an alternate embodiment of my new design including a pocket;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a bottom plan view thereof; and,

FIG. 14 is a top plan view thereof.

The broken line showing of a woman in FIGS. 1 and 8 is for illustrative purposes only and forms no part of the claimed design.
